UNITED STATES PATENT OFFICE.

HERBERT I. WASBURN, OF MAGNOLIA, NEW JERSEY.

APPARATUS FOR GUIDING INDEPENDENTLY-MOVING ELEMENTS.

Application filed September 23, 1919. Serial No. 325,797.

To all whom it may concern:

Be it known that I, HERBERT I. WASBURN, of Magnolia, in the county of Camden, and State of New Jersey, have invented 5 certain new and useful Improvements in Apparatus for Guiding Independently-Moving Elements, whereof the following is a specification, reference being had to the accompanying drawings.

10 The invention relates to apparatus for guiding independently moving elements over a spiral course, and is more specially adapted for use in connection with tractors for agricultural implements, although it 15 may, with equal facility, be employed for other analogous purposes as will become apparent from disclosure herein.

The invention is directed to means for controlling the mode of operation of the apparatus so that a change may be effected in 20 the rate of variation of the radius of the spiral traced by the guided element.

The invention is further directed to a 25 guiding apparatus of the general character above outlined, including a receiving means upon which a flexible connector is wound; mechanism for driving the receiving means; devices whereby the receiving means may be temporarily disconnected from its driving 30 means to permit unwinding of the flexible connector; and means for automatically restoring the driving engagement after a predetermined length of the connector has been unwound from the receiving means.

35 The invention also comprehends novel visual signal means whereby the operative may be assured of the automatic restoration of the driving connection above referred to from a distance, before setting the guided 40 element in motion.

The invention further includes means whereby the flexible connector is constantly lubricated during the operation of the apparatus.

45 The invention also comprehends certain novel structural details which will be better understood from the description which follows.

In the drawings Fig. I. is an elevation 50 of the guiding apparatus conveniently embodying my invention.

Fig. II. is a vertical axial sectional view of the same along the plane indicated by the arrows II.—II. in Figs. I. and III.

55 Fig. III. is a staggered plan sectional

view of the device indicated generally, by the arrows III.—III. in Fig. II.

Fig. IV. is an elevation on an enlarged scale, showing certain details to better advantage.

Fig. V. is a fragmentary section of the winding drum, illustrating more specially the details of an automatic tripping mechanism.

Fig. VI. is a partial sectional view along 65 the line VI.—VI. in Fig. III. showing details of a latch forming part of the mechanism whereby the mode of operation of the apparatus may be changed.

Fig. VII. shows in perspective a clutch 70 member cooperative with one element of a differential gear drive for the winding drum.

Fig. VIII. is a plan sectional view along 75 the line VIII.—VIII. in Fig. IV, illustrating certain details of a setting mechanism by which the drum is freed so that the wire may be manually unwound therefrom preparatory to starting the apparatus in operation.

Fig. IX. is a diagrammatic view showing 80 the relation of certain parts of the mechanism pictured in Fig. VIII.

Fig. X. is a roller associated with the 85 automatic tripping mechanism of Fig. V.

Fig. XI. is a detail sectional view along the plane of the arrows XI.—XI. in Fig. II.

The device as a whole is supported by a post 1, about which the moving element rotates, attachment being effected by means 90 of a flexible connector in the form of a wire or cable 2, which in operation, is held taut by reason of the tendency of the guided element to move tangentially, to the curvature of travel.

The course followed by the guided element is determined by the co-operation of a receiving drum 3, which may be employed as a winding or an unwinding member for the flexible connector, accordingly as to 100 whether the desired progression be toward or away from the centre post or standard.

1. The drum 3, is formed with an axial sleeve 4, which is rotatably supported within a socket member 5, adjustably secured to 105 a bracket 6 by bolts 7. Said bracket is fulcrumed about a hollow bearing extension 8, supported by a fitting 9 bolted or otherwise attached to the centre post 1. Secured within the drum is an internal gear 110

10, which is in mesh with a spur pinion 11, threaded upon the upper end of a shaft 12, extending through the bearing member 8. Directly beneath the pinion, the shaft 12, is 5 formed with a clutch member 13, which is adapted to co-operate with a corresponding clutch member, formed in the upper face of a disc flange 14, (Fig. VII) on the member 8. The two clutch elements are normally held in the engaged relation shown 10 in Fig. II, by means of a locking mechanism comprising a collar 15 secured to the shaft 12, and provided with a cam wing 16, which co-operates with a projection 17, 15 formed upon the fitting 9. At the lower end of the shaft 12 is an operating handle. Referring to Figs. VIII, and IX., it will be seen that as the wing upon the collar 15 is moved in the direction of the arrow a rigid 20 locking is effected by the wedging action, the cam inclination upon the wing being opposed to the slope of the clutch teeth. By this arrangement, the shaft 12 is positively locked against accidental displacement during the operation of the apparatus.

The drum 3 is enclosed with a protective casing 20, which has capacity for independent rotation with respect to the former, and is secured to a sleeve 21, which is received within the sleeve 4 of said drum. The inner end of the flexible connector is attached to the drum at 22 (see Fig. III), and in order that the casing may move with the same, I have provided a follower arm 23, 35 which is hinged at 24—24 to the said casing. At its outer end, said arm carries a sheave 25, which engages the connector 2. Bow springs 26—26 effective upon the follower arm serve to maintain the sheave in 40 operative contact with the connector, and also prevent rattling.

At the point where the guide wire enters the casing, the latter is provided with an off-set 27 having a hinged door 28, normally held closed, by a coiled spring 29, encircling the hinge pin 30. Mounted in suitable retainers, one formed in the wall of the offset, and the other in the door, are opposed felt pads 33—33, between which the 45 connector 2 moves as it enters the casing. By this arrangement, the pads are readily accessible to permit replenishment of the lubricant from time to time. Operating within a radial extension 35 of the casing, is an arm 36, having an integral fulcrum sleeve 37 fitting within the sleeve 21 already described. The latter sleeve is slotted as shown at 38 in Figs. II and XI, so that the arm 36 may shift vertically during 50 combined rotation of the sleeves 21 and 37. At its outer down-turned extremity arm 36, supports a sheave 40, which engages connector 2, and guides the same in its motion as it is spooled upon the drum. Referring to 55 Fig. II, it will be seen that the lower end of

the sleeve 37, is internally threaded to engage with an axial screw 42. The latter is held from relative rotation by an integral wing 43, seated within a receiving slot in the bottom of the sleeve 4. The pitch of 70 the screw is such that, as the connector is drawn upon the drum, the sleeve 37 is gradually moved upward or downward (according to the direction of travel of the guided element) so that even spooling is effected. 75

It will be noted by reference to Figs. III, and IV, that the felt pads 33, correspond substantially in extent, to the width of the drum and notwithstanding the vertical motion of the wire, are always in wiping contact with the same. As a consequence, the lubricant is constantly applied to the wire which is thus rendered proof against corrosion.

The casing 20 is closed at the bottom by 85 a diaphragm 45, which is supported by bracket 6. During certain conditions of operation of the apparatus, the casing 20 is locked in fixed relation with the diaphragm by means of a latch member 46, guided by 90 a strap 47, and adapted to co-operate with a socket member 48 on the casing as best seen in Fig. VI. The said latch member is provided with a protruding ring 49 by which it may be manually actuated from the exterior. To the inner end of the member 46 is pivoted one arm 50 of a bell-crank lever 51 fulcrumed about a pin 52 secured in the bracket 6. The other arm 53 of the lever is provided with a projection 54, which is co-operative with a notch 55 in the peripheral flange 14 of member 8. The bell-crank lever 51, is subject to the action of a spring 56, which at one end engages a fixed pin 57, and at the other, a lug 58 formed on the 100 arm 50.

From Fig. III, it will be seen that as the bell-crank lever is shifted, the spring will be transposed therewith, so as to hold said lever in either of its rest positions. 110

After the wire has been fully wound upon the drum, in order that the operative may again unwind the wire to begin operations anew, the clutch members are disconnected by turning the shaft 12 to disengage the 115 locking members 16 and 17, so that the drum may be freed for rotation, whereupon the operative may, by drawing upon the wire, readily unwind the same. In order to temporarily hold the pinion elevated, and the clutch disconnected, I have provided a holder element in the form of a double armed lever 60, having at one extremity a notched enlargement 61 which is adapted to engage under a head 62 on the top of the 120 shaft 12. The said lever is fulcrumed about a bracket 63 secured to the member 6, and is subject to the action of a coiled spring 64 which tends to force the extremity 61 125 into engagement with the head 62. The 130

other extremity 65 of the lever is adapted for co-operation with an automatic tripping mechanism which comes into play after a predetermined length of the connector is released from the drum.

This tripping mechanism includes a movable member in the form of a bell crank having the arms 66 and 67 and fulcrumed at 68 to the inner periphery of the drum. The 10 arm 66 of this member carries a roller 69 which, under the influence of a spring 70 is protruded through an opening 71, in the face of the drum so as to be engaged by the flexible connector as shown in Fig. V. 15 When in this position the hooked end of the other arm 67 of the tripping member is clear of the extremity 65 of the double armed lever 60.

However, as soon as the roller 69 is released, the hook 67 is projected by the action of the spring 70, and as the drum revolves, engages the arm 65 thereby releasing the shaft so that the latter, together with the pinion thereon drops. As a consequence 25 the clutch faces automatically re-engage, complete intermesh being established by subsequent induced rotation of the pinion. In order that the roller 69 may be restricted to engage only with the last round of the 30 flexible connector, the latter is formed as shown in Figs. V. and X. with a sharp projecting flange 72, located at the proper level to wedge between the said round and the succeeding turn of the connector. The specific purpose of this provision will become 35 apparent from the description of the operation of the device.

Under certain conditions, it is desirable to manually restore the clutch to its normal 40 operative position when the tripping of the holder element may be effected by means of a pendant chain 73, attached to arm 65 of the lever 60, and extending to the exterior of the drum enclosure through an 45 opening 74 in the diaphragm 45.

One mode of operation of the apparatus is as follows: Assuming the parts positioned as shown in Fig. III.,—i. e. the drum 3 held stationary by reason of the pinion 11 intermeshed with the internal gear 10 being locked, and the bracket 6 locked by the member 51,—rotation of the guided element in the direction of the arrow, results simply in the winding of the connector 2, 55 upon the drum. At each rotation, a length corresponding to the periphery of the drum is taken up, so that the guided element moves along a spiral course of constantly decreasing radius. In the course of this 60 operation, the arm 23 follows the connector 2, thereby causing the casing 20, to rotate independently about the drum. Similarly the guide arm 36, is induced to follow the movement of the connector through 65 the instrumentality of the engaging sheave

40. In the course of this action, the arm is guided downwardly by the co-operation of the screw 42, and as a result the connector is evenly spooled upon the drum, until it is practically all taken up, whereupon the 70 operative brings the guided element to a stop.

If it be desired to retrace the course, it is simply necessary to reverse the direction of travel in a direction opposite to that 75 indicated by the arrow in Fig. III., when the several co-operative parts of the apparatus will obviously operate conversely in permitting a gradual unwinding of the connector, the increment of change in the 80 effective length of the connector for each convolution of the spiral course traced, being the same as before.

If instead of resorting to the last procedure, it is desired to begin anew, the operation first described, the operative proceeds as follows: The handle at the lower end of shaft 12, of the locking mechanism is turned so as to disengage the cam 16 from the projection 17, and the shaft together with 90 pinion 11, thence raised to disengage the clutch.

As a consequence, the holding member 61 under the action of the spring 64 automatically slips beneath the head 62, on the 95 top of the shaft 12. The drum 3, thus freed, may be readily rotated to permit the withdrawal of the connector, until unwinding has proceeded to the point shown in Fig. III. Directly before reaching this 100 point, the tripping element had been released so that its hooked end shifted into the path of the extremity 65, of the tripping element, and through rotation of the drum, engaged the same to withdraw the notched holder from beneath the head 62, of the 105 shaft 12, thereby permitting the latter to drop, and effecting automatically, the re-engagement of the clutch. It may be well to repeat at this point, that through the 110 reversed inclination of the locking members 16 and 17, with respect to the clutch teeth, the induced rotation of the pinion tends firstly to establish, and thereafter to maintain the interlock between these parts.

In order that the operative may ascertain from a distance (after the wire connector has been withdrawn to the predetermined limit) as to whether or not the automatic coupling of the clutch members has 115 taken place, I have provided, as shown in Fig. I. a semaphore 80, having contrasting colorings upon opposite sides. This semaphore is attached to the shaft 12, and the respective colorings are displayed in accordance with the alternative positions of the latter.

I have also secured an indicator in the form of an arrow 81, to the top of casing 20, (see Fig. I. and IV.) so that the general 130

behavior of the apparatus may be observed from a comparatively remote point.

Again, if it be desired to reset the clutch at any point within the limits of the guide wire, this may be accomplished by tripping the holder lever 60, manually, by pulling upon the pendant chain 73.

In effecting the other mode of operation of the apparatus, the operative shifts the latch 46, to secure the casing 20, against independent rotation relative to the drum 3, and at the same time by virtue of the connection of the bell crank lever 51, with said latch causes the disengagement of the projection 54, and the disk flange 14, of the bearing member 8. As a result of these preliminary steps, the axis of rotation of the guided implement is transferred to the fulcrum bearing 8, and the drum moves bodily about said axis under the support of the bracket 6. The drum is now, however, free to rotate independently with respect to the pinion 11 so that a differential action takes place.

25 Thus for each rotation of the guided implement, the drum is shifted counterwise with respect to the direction of said rotation; the length of the wire taken up in each instance depending of course upon 30 the ratio of the gears. In other respects the operation of the apparatus is similar to that previously described, and repetition would therefore be superfluous in this connection.

35 It will be observed that in the latter mode of operation; the increment of variation, which determines the spacing of the convolutions of the spiral path over which the independently moving element is guided, is 40 considerably less than in the first case. The apparatus may therefore be accordingly set to guide the independently movable element either for cultivating or ploughing as may be desired.

45 If further variation should be desired in the "swath" determined by the apparatus, the pinion 11, may be replaced by others of larger or smaller dimensions whereby the gear ratio is correspondingly changed. In 50 order to permit such substitution, the several parts carried by the bracket 6, protrude through openings in the diaphragm 45, so that the latter together, with the socket member 5, may be shifted and the drum re- 55 adjusted to accommodate the change, and thereafter re-clamped by the bolts 7 into fixed position.

Having thus described my invention, I claim:

60 1. In an apparatus for guiding independently moving elements, the combination of a drum; a flexible connector adapted to be wound on said drum; driving means for the drum; devices for disconnecting said drum from its driving means to permit the

unwinding of the flexible connector therefrom; and means for automatically reconnecting the driving means after a predetermined length of the flexible connector has been unwound from the drum. 70

2. In an apparatus for guiding independently moving elements, the combination of a drum; a flexible connector adapted to be wound upon said drum; driving means for the drum; a clutch whereby said drum may be disconnected from this driving means to permit the unwinding of the flexible connector; and means for automatically restoring said clutch to activity after a predetermined length of the connector has been unwound from the drum. 80

3. In an apparatus for guiding independently moving elements, the combination of a drum; a flexible connector adapted to be wound upon said drum; driving means for the drum; a clutch whereby the drum may be disconnected from its driving means to permit the unwinding of the flexible connector, and means carried by said drum for automatically restoring said clutch to activity after a predetermined length of the connector has been unwound. 90

4. In an apparatus for guiding independently moving elements, the combination of a drum; a flexible connector adapted to be wound upon said drum; driving means for the drum; a clutch for the said driving means; means whereby said clutch may be temporarily held disengaged to permit unwinding of the flexible connector; and a tripping mechanism for releasing the holding means to permit the restoration of the clutch to activity after a predetermined length of the connector has been unwound from the drum. 100

5. In an apparatus for guiding independently moving elements, the combination of a drum; a flexible connector adapted to be wound upon said drum; driving means for the drum; a clutch for said driving means; a holding element whereby said clutch may be temporarily held disengaged to permit unwinding of the flexible connector from the drum; a tripping element normally held retracted when the drum is loaded, but which upon the departure of the last round of the connector is automatically projected to engage the holding element to effect release of the clutch to activity. 110

6. In an apparatus for guiding independently moving elements, the combination of a drum; a flexible connector adapted to be wound upon said drum; driving means for the drum; a clutch for said driving means; a holding element whereby said clutch may be temporarily held disengaged to permit unwinding of the flexible connector from the drum; a tripping element normally held retracted by the final round of the connector upon the drum, but which upon the depa- 120

115

120

125

130

ture of said round, is automatically projected to engage the holding element to effect release of the clutch to activity.

7. In an apparatus for guiding independently moving elements, the combination of a drum; a flexible connector adapted to be wound upon said drum; driving means for the drum; a clutch for the driving means; a holding element whereby said clutch may be temporarily held disengaged to permit unwinding of the flexible connector from the drum; a spring pressed tripping element pivoted intermediate its ends to the inner periphery of the drum; a roller carried upon one extremity of said element, and adapted to protrude through an opening in the drum to be engaged by the coiled connector whereby the opposite extremity of said element is normally held retracted, but upon the departure of the last round of the connector is freed so as to project into engagement with the holding lever to effect a release of the clutch to activity.

8. In an apparatus for guiding independently moving elements, the combination of a drum; a flexible connector adapted to be wound upon said drum; a protective casing surrounding the drum, said casing having an opening for the passage of the connector; and lubricating pads arranged at the sides of the opening in wiping contact with the connector.

9. In an apparatus for guiding independently moving elements, the combination of a drum; a spooling mechanism, a flexible connector; a protective casing surrounding the drum, said casing having a slotted opening; and lubricating pads arranged at the sides of the opening, between which the connector passes in wiping contact as it is shifted laterally of the drum in the spooling operation.

10. In an apparatus for guiding independently moving elements, the combination of a drum; a flexible connector adapted to be wound upon said drum; a protective casing surrounding the drum, said casing having an opening for the passage of the connector; lubricating pads arranged at the sides of the opening in wiping contact with the connector one of said pads being mounted in a retractible holder to permit access for the replenishing of the lubricant.

11. In an apparatus for guiding independently moving elements, the combination of a drum; a flexible connector adapted to be wound upon said drum; a protective casing freely rotatable about said drum; and means for effecting movement of the casing under the propulsion of the flexible connector.

12. In an apparatus for guiding independently moving elements, the combination of a drum; a flexible connector adapted to be wound upon said drum; a protective casing freely rotatable about the drum; and

means for effecting movement of the casing under the propulsion of the flexible connector, said means including a follower-arm pivotally attached to the casing, and having at its outer end sliding engagement with the flexible connector.

13. In an apparatus for guiding independently moving elements, the combination of a drum; a flexible connector adapted to be wound upon said drum; a supporting bracket for the drum capable of rotating about a fixed bearing member in one mode of operation of the apparatus; and means for locking said bracket to its bearing in effecting another mode of operation of the apparatus; said locking means including a finger pivoted upon the bracket and adapted to engage within a notch in a disc flange formed upon the bearing member.

14. In an apparatus for guiding independently moving elements, the combination of a drum; a flexible connector adapted to be wound upon said drum; a protective casing freely rotatable about the drum; a supporting bracket for the drum capable of rotating about a fixed bearing member in one mode of the operation of the apparatus; and means for simultaneously locking said protective casing against free rotation relative to the drum, and the bracket into fixed relation with its bearing member in effecting another mode of operation of the apparatus.

15. In an apparatus for guiding independently moving elements, the combination of a rotatable drum; a flexible connector adapted to be wound upon said drum; a driving gear pinion for the drum; a clutch for said pinion; means for axially shifting said pinion to disengage the clutch; means for temporarily holding said pinion in its shifted position to permit unwinding of the connector from the drum; and means for automatically actuating the holding means to release said pinion to permit the restoration of the clutch to activity, after a predetermined length of the connector is unwound from the drum.

16. In an apparatus for guiding independently moving elements; the combination of a rotatable drum; a flexible connector adapted to be wound upon said drum; a driving means for the drum; a clutch for said driving means; a shaft associated with said clutch; a hand lever whereby said shaft may be axially shifted to disengage the clutch; a head on said shaft; an element adapted to engage beneath the head to temporarily hold said shaft in its shifted position to permit unwinding of the connector from the drum; and means for automatically tripping said element to release the shaft, and thereby permit restoration of the clutch to activity after a predetermined length of the connector is unwound from the drum.

17. In an apparatus for guiding independently moving elements; a combination of a drum; a flexible connector adapted to be wound upon said drum; driving means for the drum; a clutch for the driving means; a shaft capable of being shifted longitudinally to disengage the clutch, means for temporarily holding the shaft in its shifted position to permit unwinding of the drum; 10 means for automatically actuating the holding means to release said shaft and permit the restoration of the clutch to activity after a predetermined length of the connector is unwound from the drum; and means for 15 simultaneously effecting the automatic locking of the clutch, the latter means including co-operative, relatively movable, engaging cam members associated with said shaft and inclined in opposition to the induced 20 rotation of the same.

18. In an apparatus for guiding independently movable elements; the combination of a drum; a flexible connector adapted to be wound upon said drum; a driving 25 means for the drum; devices for disconnecting the drum from its driving means to permit the unwinding of the flexible connector therefrom, means for automatically connecting the drum with its driving means after 30 a predetermined length of the flexible connector has been unwound from the drum; and a signal device associated with the latter means visible from a remote point whereby the operator may be assured of its automatic operation before starting the guided 35 element in motion.

19. In an apparatus for guiding independently movable elements; the combination of a rotatable drum; a flexible con-

nector adapted to be wound upon said drum; 40 means for driving said drum; a clutch for said driving means; a rotatable shaft for shifting said clutch to permit unwinding of the connector from the drum; means for releasing said shaft to permit the automatic 45 restoration of the clutch to activity after a predetermined length of the connector is unwound from the drum; and a semaphore signal mounted on the clutch shifting shaft, visible from a remote point so that the 50 operator may be assured of the proper operation of the clutch before starting the guided element in motion.

20. In an apparatus for guiding independently moving elements, the combination of a drum; a flexible connector adapted to be wound upon said drum; a rotatable protective casing for the drum; and a visible 55 indicator on said casing whereby the movement of the apparatus may be observed from 60 a remote point.

21. In an apparatus for guiding independently moving elements, the combination of a connector, a take-up means for the connector, operating means for the take-up 65 means normally inactive to permit withdrawal of the connector, and means operable automatically after the connector has been sufficiently withdrawn to initiate operation of the operating means to retract 70 the connector.

In testimony whereof, I have hereunto signed my name at Philadelphia, Pennsylvania, this 22nd day of September 1919.

HERBERT I. WASHBURN.
